CONTAINER WITH WATER SHEDDING
TOP CONSTRUCTIONCarl G. Preis, Forest Hills, N. Y., assignor to
American Can Company, New York, N. Y., a
corporation of New Jersey

Application April 14, 1949, Serial No. 87,402

4 Claims. (Cl. 229—7)

1

The present invention relates to containers for the packaging and delivery of liquids, such as milk and has particular reference to a sanitary fibre container having a top construction which will readily shed water and other foreign matter.

The invention constitutes an improvement upon the container illustrated and described in United States Patent 2,246,518 issued June 24, 1941 to John M. Hothersall on Container, and is especially an improvement on the top construction thereof.

The invention contemplates a container top member which is secured to the body of the container by an interfolding of marginal edge portions of the top and the body members in an end seam, the top member being domed so that its outer or upper surface is above the plane of the major portion of the surrounding end seam and being surmounted by an embossment which includes a dispensing opening and a portion of the end seam, the embossment and included portion of the end seam extending above the top member and the major portion of the end seam.

An object of the invention is the provision of a sanitary fibre container for milk and other beverages wherein the top member is formed so that water or other foreign matter is prevented from collecting on the top of the container with special protection for that portion of the top member that includes the dispensing opening, thus preventing contamination of these surfaces.

Another object is the provision of such a container wherein the domed top member is provided with a raised embossment which includes a portion of the container end seam and a dispensing opening and which with its inclusions is elevated above the top member and the major portion of the end seam to insure draining away from the embossment any water or other foreign matter and thus maintain the top surfaces of the embossment free from contamination.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a container embodying the instant invention, with a portion broken away and clearly illustrating the embossment which surrounds the dispensing opening and also showing the closure in an open position;

Fig. 2 is an enlarged top plan view of the container shown in Fig. 1 with the closure element in a closed position; and

2

Figs. 3 and 4 are enlarged sectional views of the top portion of the container as viewed substantially along the respective lines 3—3, 4—4 in Fig. 2.

5 As a preferred or exemplary embodiment of the instant invention the drawing discloses a fibre container comprising a substantially rectangular tubular body 11 closed at its ends with top and bottom members 12, 13 (Fig. 1). The body 11 preferably is formed from a single sheet of fibrous material folded at right angles to provide four side walls 15, the short edges of the sheet being overlapped in a vertical lap side seam 16. The marginal edges of the seam preferably are secured with a suitable adhesive so that a liquid tight side seam results.

The top and bottom members 12, 13 preferably are squares of fibre material which are interlocked with the adjacent end or marginal terminal portions of the body. For this purpose the body marginal end portions are bent obliquely inwardly as at 18 and thence outwardly as at 19 thereby providing ledges 21 on which the members 12, 13 are supported. The extreme edges of the body marginal terminal portions are thence bent inwardly over the outer marginal edges of the members 12, 13 thus providing opposite end flanges 22 which hold the members in place.

20 The flange parts 19, 22 of the body adjacent its ends and the edges of the top and bottom members 12, 13 preferably are secured with a suitable liquid proof adhesive. This manner of construction provides a liquid tight end seam which generally is indicated by the numeral 25.

25 The bottom member 13 preferably is flat throughout. In contrast to this the top member 12 is formed with a raised domed or pyramidal shaped panel 27 which is pressed or struck outwardly from the material of the member and which preferably comprises four flat triangular shaped and inclined surfaces 28. The area of the panel preferably extends over the entire area of the container top inward of the inner edge of the top end seam flange 22 and thereby fits tightly against the inner edge of the top end seam. The panel also extends above the plane of the end seam and practically merges into the end seam in a stepped panel section or reinforcing shoulder 29 thereby providing a smooth or flush connection between the panel and the seam.

30 This construction of top member prevents collection of water, such as rain water, ice water, or any other foreign matter on top of the container, any such matter immediately running off or draining away over the smooth end seam 25 so that the top member will be left clean.

3

The top member 12 is further provided with a raised boss, platform or embossment 31 which is superimposed upon or surmounts the domed panel 27 and which includes a flat top surface 32 having a dispensing opening 33 formed therein. The boss 31 preferably is located adjacent one corner of the container top although it could equally well be located adjacent a side of the top or any other desired location. All portions of the boss 31 extend above the domed panel 27 so that the top surface of the boss is elevated above the parts of the top member. This boss preferably starts substantially at the geometrical center of the panel 27 of the top member 12 and extends outwardly and preferably horizontally 15 (as shown in Fig. 3) to the outer edge of the top member including the end seam 25.

The outer edge of the boss portion of the top member 12 is incorporated in an elevated portion 34 of the end seam 25 and is formed with a re-enforcing shoulder 35 (Fig. 3) which provides for a tight fit against the inner edge of the seam and which makes the top flange 22 of this elevated portion 34 of the seam, flush with the top of the boss 31 for use as a pouring surface when the contents of the container are dispensed. The elevated portion 34 of the end seam 25 merges into the remaining portion of the seam on both sides of the boss 31 in abrupt sharply sloped shoulders 36 which also merge laterally into similarly sloped shoulders 37 of the boss itself. The shoulders 37 extend completely around the boss 31 from the seam shoulder 36 on one side of the container top to the seam shoulder 36 on the opposite side of the top, thus forming a relatively high barrier around the boss.

Thus any foreign matter impinging against the top of the container is readily shed or directed away from the top surface of the boss 31 by the shoulders 36 in the end seam and the shoulders 37 around the boss. This shedding or draining of foreign matter from the top of the container is of particular value when tilting the container into position for dispensing the contents therefrom.

The dispensing opening 33 preferably is closed and the top surface 32 of the boss 31 covered and protected by a hinged closure element 42 which is similar to that disclosed in the above mentioned Hothersall patent. The closure element is secured by a staple 43 to the top of the boss 31. This closure element is substantially the same shape and dimensions as the top of the boss 31 and covers the entire top surface 32 of the boss. A portion of the element is formed with a friction plug 44 which fits tightly into the dispensing opening 33 and which is expanded under the boss 31 to keep it in place when the container is filled and closed. Adjacent the elevated portion 34 of the seam 25, the closure element 42 is formed with a depending skirt portion 46 (Figs. 1, 2 and 3) which extends over the seam and is bent upwardly under the seam as shown in Fig. 3 to keep the closure element in place.

In this manner the top surface of the boss 31 and the adjacent elevated portion 34 of the end seam 25 which is used as a pouring surface when the contents are dispensed from the container, are maintained in a clean, sanitary condition. In opening the container by the raising of the closure element 42, any water or other foreign matter that may be in the recess of the friction plug 44 is emptied onto the domed shaped panel 27 below the boss 31 and is immediately drained away from the boss and the surrounding con-

tainer top by virtue of the domed shape of the top walls and the barrier around the boss and is thereby prevented from coming into contact with the contents of the container.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container for liquids comprising a tubular fibre body terminating in a peripheral flange, a fibre top member having its marginal edge portions secured to said body flange in an end seam, said top member inside of said end seam being formed with a domed panel disposed above the top plane of the major portion of said end seam, a raised embossment integrally formed in said top member and extending outwardly toward and incorporated in an adjacent portion of said end seam, said incorporated seam portion being raised above the remaining seam to insure said embossment having a flat top surface flush with the raised portion of the end seam to provide an unbroken elevated pouring surface for dispensing the contents of the container, a dispensing opening in said embossment, and a closure element for said dispensing opening, said closure element when in closed position extending over and covering the pouring surface of said embossment and the adjacent portion of said end seam, said embossment and the raised portion of said end seam providing abrupt shoulders for said embossment which merge into sloped shoulders at the junction of the raised and the unelevated portions of said end seam for shedding from said domed panel and over the unelevated portion of said end seam undesirable extraneous foreign matter, whereby to insure against contamination of the container contents.

2. A container for liquids comprising a tubular fibre body terminating in a peripheral flange, a fibre top member having its marginal edge portions united with said body flange in an end seam, said top member being formed with a domed panel extending upwardly from inside of said seam, a raised embossment integrally formed in said top member and extending above said domed panel and into a portion of said end seam, a dispensing opening in said embossment adjacent the end seam, the end seam portion contained in said embossment being elevated above the remaining portion of the seam to form a flat surface with said embossment to provide a barrier around said dispensing opening for shedding undesirable extraneous foreign matter from the top member to insure against contamination of the container contents, and a closure element for closing said dispensing opening.

3. A container for liquids comprising a tubular fibre body having angular corners and terminating in a peripheral inwardly extending flange, a fibre top member having a domed panel and angular corners and having its marginal edge portions secured within said body flange in an end seam, a raised embossment integrally formed in the domed panel of said top member and extending from the central portion thereof into one of the corners of the top member and including a portion of the end seam which is elevated above the remaining portion of the seam, outer

edges of said embossment adjacent said included corner abutting against the included inner edges of said inwardly extending terminal flange of said body to constitute with the raised portion of said end seam a substantially continuous and flush pouring surface adjacent said dispensing opening for shedding extraneous foreign matter from said top member, and a closure element hingedly secured to said embossment at one side of said opening for closing and sealing the container to insure against contamination of the container contents.

4. A container for liquids comprising a tubular fibre body terminating in a peripheral flange, a fibre top member having its marginal edge portions united with said body flange in an end seam, said top member being formed with a domed panel extending upwardly inside of said seam, a raised embossment integrally formed in said top member and an adjacent part of said end seam and having a flat top surface extending above said domed panel and the remaining lower part of said seam, said flat top surface having a dispensing opening therein for said container and merg-

ing with said panel and lower seam part in sloped shoulders, and a closure element for said dispensing opening, said closure element having a flat portion substantially the same in shape and dimensions as said flat surface of the embossment for entirely covering said surface, said closure also having a depending portion extending from said flat portion and over the adjacent part of said end seam, said shoulders directing away from said flat surface any foreign matter impinging against the top of said container to insure against contamination of the container contents.
